UNITED STATES PATENT OFFICE

EDWARD McCANDLISH, OF NORTHLVILLE, MICHIGAN, ASSIGNOR TO S. S. KRESGE COMPANY, OF DETROIT, MICHIGAN, A CORPORATION OF MICHIGAN

DESIGN FOR A DOLL

Application filed March 20, 1931. Serial No. 39,174. Term of patent 3½ years.

To all whom it may concern:

Be it known that I, EDWARD McCANDLISH, a citizen of the United States, residing at Northville, in the county of Wayne and State of Michigan, have invented a new, original, and ornamental Design for a Doll, of which the following is a specification, reference being had to the accompanying drawings, forming part thereof.

Fig. 2 is a side elevation, and

Fig. 3 is a rear elevation thereof.

I claim:

The ornamental design for a doll as shown.

EDWARD McCANDLISH.
